UNITED STATES PATENT OFFICE.

JOSEPH LOUIS ROUTIN, OF PARIS, FRANCE.

APPARATUS FOR CONTROLLING MOVEMENTS AT A DISTANCE.

1,409,586.

Specification of Letters Patent. Patented Mar. 14, 1922.

Application filed June 24, 1919. Serial No. 306,476.

To all whom it may concern:

Be it known that I, JOSEPH LOUIS ROUTIN, a resident of Paris, in the Republic of France, have invented new and useful Improvements in Apparatus for Controlling Movements at a Distance, which invention is fully set forth in the following specification.

The present invention relates to electrical apparatus for indicating and repeating angular movements at a distance, and more particularly to apparatus of the above class in which an annular rheostat is situated at a transmitting station and is connected through a source of current to one or more like rheostats at the receiving stations. The exact repetition of the movements being transmitted from one station to the other is controlled by the maintenance at zero of the needle of a voltmeter included in a conductor connecting the brushes of the two rheostats.

In such apparatus as heretofore constructed, it may happen that the degree of exactness of the transmission is diminished if one of the receivers is rendered stationary for any reason. The current which then flows through the volt-meter of this receiver has a tendency to disturb the uniformity of distribution of the voltage in the rheostat of the transmitter.

The present invention has for its object to provide an improvement which will enable that drawback to be avoided by producing the absolute independence of each of the receivers. This present improvement allows also of indicating at the transmitting station the correct placing of the parts to be controlled, and of indicating when necessary, which part or parts is or are not correctly placed.

The accompanying diagrammatic drawing illustrates by way of example one constructional form of the improvement of the present invention.

1 is the rheostat of the transmitting station;

3—3 are the rheostats of the receiving stations;

2 is the axle around which the brushes 5 and 7 revolve;

4 is the axle around which the brushes 6 and 8 revolve;

15 is the battery that feeds the rheostats;

9—9 are the voltmeters of the receiving stations, each provided with two windings 20 and 21.

In the accompanying drawing is shown a Wheatstone bridge in one branch of which is located a rheostat 1 at the sending station, and in companion branches are two or more rheostats 3, 3 located at the receiving stations. These rheostats are branched in parallel from a common source of current such as a battery 15. In bridge circuits connecting the brush elements of these rheostats are voltmeters 9, 9. The exact repetition of the movements transmitted from the sending station to the receiving stations is controlled by maintaining the needles of the voltmeters at zero.

In order to maintain the absolute independence of the receivers and to secure other objects of the present invention, I provide conducting brush elements 5, 7, mounted on an insulating arm pivoted at its center 2, which wipe the rheostat coil 1. Similar double brushes 6, 8 at the receiving stations are adapted to rotate about pivots 4, 4 and wipe rheostat coils 3, 3. Brush elements 5, 7 of the transmitting station rheostat are connected in circuit with voltmeters 25, 26 with switch arms 31, 32 which are adapted to be rotated by a motor 24 and to wipe pairs of distributor contacts 22, 23. The contacts of pair 22 are connected in bridge circuits with coils 20, 20 of voltmeters 9, 9 and the contacts of pair 23 are connected with coils 21, 21 of the same voltmeters. Brush 5 of the sending station rheostat is adapted to be connected through distributor terminals 22 with either of brushes 6, 6 through voltmeter coils 20, 20, and brush 7 of the sending station rheostat is adapted to be connected with either of the brushes 8, 8 through distributor terminals 23 of the same voltmeters.

The association of two brushes such as 5, 7 and 6, 8 assures the continuous indication by the voltmeter needle in spite of the break successively produced in each of the circuits 5—6 and 7—8 when the corresponding brushes find themselves in the zone which separates the two ends of the rheostat, as more fully explained in my Patent No. 1,402,096, issued Jan. 3, 1922. At times, both brushes 5 and 7, for instance, may wipe the spires of the rheostat. The sensitiveness of the voltmeter will be increased by the resulting increase of current. The operation of the system is in no way interfered with by this fact since only zero reading on the voltmeters are taken.

The improvement according to the present invention consists in this that 20 and 21 are now connected only in a temporary manner to the contacts 5 and 7 of the transmitter, in such a manner that the windings of the several voltmeters will be placed successively in operation, and there will never be two receiving voltmeters in simultaneous operation.

Under these conditions the possible reactions which an accidentally stopped receiver may have upon those that remain in operation, will be completely eliminated. The distributors 22 and 23 which allow of effecting this cutting-out of circuit, consist of fixed contact pieces arranged in a circuit at which terminate respectively the ends of the windings 20 and 21, and of two revolving contact pieces which are connected respectively to 5 and 7. These revolving contacts are actuated by a small motor 24.

It is evident that, when all of the receivers are correctly placed, the conductors which are connected to the contacts 5 and 7 of the transmitting station are never traversed except by a current of very feeble intensity. In order to insure that all of the receivers are correctly placed, it suffices, therefore, to install two milliamperemeters 25 and 26 on the said conductors. If the index of the voltmeters 25 and 26 do not rest in the neighborhood of zero, it would be concluded that one, at least, of the receivers is not correctly placed. In the case where it is necessary to be able to know at the transmitting station which receiving station is not executing correctly the orders transmitted, it is necessary to introduce the milliamperemeters 27, 28, 29 and 30 on each of the conductors which connects the voltmeters 9 to the distributors 22, 23.

What I claim is:

1. Apparatus for controlling movements at a plurality of receiving stations from a transmitting station comprising a Wheatstone bridge including a source of current, said bridge having one branch located at the transmitting station and having a plurality of companion branches individual to said receiving stations, a bridge circuit between said transmitting station and each of said receiving stations including a voltmeter for each receiving station and means for varying the relation of the resistances in each branch of said bridge, and switch means for successively closing the current paths through said voltmeters.

2. Apparatus for controlling movements at a plurality of receiving stations from a

transmitting station comprising a Wheatstone bridge including a source of current, said bridge having one branch including a rheostat located at the transmitting station and having a plurality of companion branches including rheostats individual to said receiving stations, a bridge circuit between said transmitting station rheostat and each of said receiving station rheostats including a voltmeter at each receiving station, movable contacts for varying the relation of the resistances in said rheostats, a motor-driven switch arm, and a conductor including a voltmeter connecting said arm and a movable contact of the sending station rheostat and adapted to successively close said bridge circuits.

3. Apparatus for controlling movements at a plurality of receiving stations from a transmitting station comprising a Wheatstone bridge including a source of current, said bridge having one branch located at the transmitting station and having a plurality of companion branches individual to said receiving stations, a bridge circuit between said transmitting station and each of said receiving stations including a voltmeter for each receiving station and means for varying the relation of the resistances in each branch of said bridge, and motor-driven switches for successively closing said bridge circuits.

4. Apparatus for controlling movements at a plurality of receiving stations from a transmitting station comprising a Wheatstone bridge including a source of current, said bridge having one branch including a rheostat located at the transmitting station and having a plurality of other branches including rheostats individual to said receiving stations, a bridge circuit between said sending station rheostat and each of said receiving station rheostats, each branch including a voltmeter at each receiving station and a milliamperemeter at the sending station, movable contacts for varying the relation of the resistances in said rheostats, a motor-driven switch arm, a conductor including a voltmeter connecting said arm, and a movable contact of the sending station rheostat, said switch arm being adapted to successively close said bridge circuits.

In testimony whereof I have signed this specification.

JOSEPH LOUIS ROUTIN.
